SCREED SUPPORT

Lambert J. O'Neill, Jr., Staten Island, N. Y., assignor to Poirier & McLane Corporation, a corporation of New York

Application February 25, 1939, Serial No. 258,529

4 Claims. (Cl. 72—128)

This invention relates to a support for a leveling device such as a screed or the like.

One of the objects of this invention is to provide a screed support which is simple and inexpensive in construction, yet sufficiently sturdy to rigidly support a screed. Another object is to provide a device of the above nature which may be secured in proper position and which is adjustable so as to vary at will the elevation of the path of operation of the screed. Further objects will be in part apparent and in part pointed out hereinafter.

The invention accordingly consists in the features of construction, combinations of elements, and arrangements of parts as will be exemplified in the structure to be hereinafter described and the scope of the application of which will be indicated in the following claims.

In the drawing in which is shown one of the embodiments of my invention:

Figure 1 is a transverse section of a concrete road or the like partly broken away with a pair of screed supports in operative position;

Figure 2 is a side elevation of one of the screed supports shown in Figure 1; and

Figure 3 is an enlarged section taken along the line 3—3 of Figure 2.

Similar reference characters refer to similar parts throughout the several figures of the drawing.

In the pouring of concrete roads or the like where the concrete is poured to a substantial depth and width and where the surface of the concrete is to be uniformly leveled, screeds of various types are employed. Screeds such as are used in leveling concrete roads are quite heavy and are usually operated by machinery which jigs the screed longitudinally and at the same time advances it along the road so as to level off the concrete. Rails at the opposite sides of the road are provided on which the screed rides during its leveling operation. These rails, in turn, have to be supported and maintained at a proper elevation from the concrete form or forms. Because of the substantial weight of the screed, the screed rails are preferably massive and, therefore, in turn, require a substantial support.

It is in the support and vertical adjustment of the screed rails that considerable difficulty is encountered. For various reasons, the depth of concrete may vary not only longitudinally of the road but also laterally thereof. Accordingly, the screed rails must be raised or lowered at various steps with respect to the concrete forms in order to maintain the uniformity of the exposed sur-

face of the concrete. Furthermore, it is undesirable that any portion of the screed support extend above the screed rail so as to interfere in any manner with the operation of the screed. Still further, the screed rails must be rigidly held in adjusted position against vertical or lateral collapse with respect to the road surface, as replacement of the screed rail subsequent to the pouring of the concrete is extremely difficult. It is a further object of this invention to obviate the above difficulties in addition to others.

With reference to Figure 1 of the drawing, a pair of screed supports are generally indicated respectively at 10 and 11. As these supports are identical, only one will be described. Support 10 comprises one of an indefinite number of similar supports located at suitably spaced centers along one side of the road secured to a form 12. Support 11 comprises one of a similar series on the opposite side of the road also secured to form 12. Supports 10 and 11 respectively carry screed rails 13 and 14, which extend longitudinally of the road and support a screed bar 15. After the concrete 16 has been poured, screed bar 15 is moved along rails 13 and 14 to level off the upper surface of the concrete.

Screed support 10 (Figure 2) includes a base or chair generally indicated at 17 having a plurality of legs 18; preferably three or more legs are provided. The lower ends of legs 18 are bent to form feet 19, while the upper ends of the legs are bent vertically to form attaching arms 20. Arms 20 are welded or otherwise secured to a coil 21 (see Figure 3) which forms a threaded socket for the reception of a lag generally indicated at 22. The opposite ends 22a and 22b of lag 22 are provided with threads of opposite pitch, end 22a being adjustably threadable in and through socket coil 21. Preferably the upper end of chair 17 supports a washer 23 disposed about lag end 22a and against which a lock nut 24 may be taken up to lock lag 22a in any desired position in socket coil 21.

The upper end 22b (Figure 3) of lag 22 is threadably received in a yoke or screed rail carrier generally indicated at 25. Yoke 25 comprises a coil 26 forming threaded socket similar to socket coil 21. Socket coil 26 is suitably secured, as by welding for example, to a pair of bars or rods 27, 28 which extend vertically upwardly from the socket. These rods are suitably spaced by reason of their attachment to opposite sides of the socket and are welded to a U-shaft bracket 29. The bottom 29a of bracket 29 extends across the space between rods 27 and 28 and forms a

carrying member for screed rail 13 (see Figure 1). Bracket 29 also serves to rigidify rods 27 and 28 and to hold them in proper alignment.

Referring back to Figure 3, it will be noted that lag 22 includes an unthreaded portion 22c which forms a suitable grip for a pipe wrench by which the lag may be rotated in one direction or another to raise or lower yoke 25 to any desired position within the scope of adjustment of lag 22. As hereinbefore noted, nut 24 may be threaded down against washer 23 and thus the lag may be securely locked as adjusted.

The specifications on concrete jobs often prohibit exposed metal surfaces after the job is poured. To this end (with reference to Figure 1), feet 19 of chair 17 preferably rest on suitable blocks 30 formed of concrete or other suitable non-metallic material, and nails 31 are driven through feet 19 and blocks 30 into form 12 to hold chair 17 securely in place. Thus, the only exposed portions of the lower end of screed support 10 are the small ends of nails 31 and this is not objectionable. Additionally, this manner of securing the screed support to the form is advantageous as it precludes the necessity of drilling holes in the form to receive a portion of the screed support.

With reference to Figures 1 and 2, it will be noted that screed rail 13 extends a substantial distance above the top of yoke 25. Thus when the concrete 16 (Figure 1) is poured, its upper surface after leveling by screed 15 is well above the top of screed support 10, thus completely enclosing the support. After the concrete has set sufficiently to permit removal of screed rail 13, the portion of screed support 10 which is left exposed by the removal of the screed rail may be patched in any suitable manner so as to cover up any exposed metal. Furthermore, by reason of the fact that the upper end of carrier yoke 25 terminates below the upper surface of screed rail 13, the screed support itself in no way impedes travel of screed 15 along the rails.

As shown in Figure 1, my screed support is adapted to carry a supplemental screed rail 40. Such an additional screed rail is often desirable where different concrete levels are specified. The elevation of the upper surface of rail 40 is predetermined in accordance with the upper surface of rail 13 so that the proper space between the surfaces is always preserved. Hence, raising or lowering yoke 25 by manipulation of lag 22 properly and uniformly adjusts both upper surfaces of both rails 13 and 40.

It may now be seen that screed support 10 may be accurately and securely positioned on form 12 and attached thereto by nails 31 driven through the feet 19 of the support. Also, the pro-

tection of legs 18 provides substantial rigidity and practically precludes lateral or longitudinal displacement of the screed support with respect to the road. By reason of the threaded ends of lag 22, vertical adjustment of the screed rails may be accurately and rigidly effected and such vertical adjustment may be maintained by lock nut 24. As noted before, the screed support terminates below the concrete level and hence does not impede operation of the screed.

Thus, I have provided an adjustable screed support which attains the various objectives hereinabove set forth in a thoroughly practical and efficient manner.

I claim:

1. A screed support comprising, in combination, a base member a threaded lag mounted in said base member and vertically adjustable with relation thereto upon rotation of the lag, a threaded socket threadably mounted on the upper end of said lag and movable axially thereof upon rotation of the lag, and a yoke secured to said socket and raisable and lowerable upon rotation of said lag.

2. A screed support comprising, in combination, a base member including a coil forming a threaded socket, a threaded lag adjustably positioned in said coil, and a second coil threadably mounted on the upper end of said lag, whereby rotation of the lag effects vertical adjustment of said second coil.

3. A screed support comprising, in combination, a base member adapted to be secured to a form, said base member including a plurality of feet, an individual support for each of said feet adapted to be interposed between the feet and the form, said support including a threaded portion, a threaded lag mounted in the threaded portion of said support and adjustable in relation thereto, means for locking said lag in an adjusted position, a threaded member carried by the upper portion of said lag, and a screed supporting bracket secured to said threaded member.

4. A screed support comprising, in combination, a base member adapted to be secured to a form, a threaded lag secured to said base member and extending upwardly therefrom, the upper end of said lag being threaded, a threaded part carried on said threaded end of said lag and adapted to support a screed rail, rotation of said lag with respect to said part being adapted to effect movement of said part axially of said lag to adjust said part at a desired height, and means for locking said lag against rotation to maintain said part in its adjusted position.

LAMBERT J. O'NEILL, JR.
